Des. 179,428
Patented Dec. 18, 1956

179,428

BEDFRAME SUPPORT LEG

Melvin E. Roche, Strongsville, and Leslie K. Jackson, Lakewood, Ohio, assignors to The Harvard Manufacturing Company, Cleveland, Ohio, a corporation of Ohio

Application October 19, 1954, Serial No. 32,716

Term of patent 14 years

(Cl. D5—2)

FIG. 2

FIG. 1

FIG. 4

FIG. 3

Fig. 1 is a view in perspective of a bedframe support leg, showing our new design;

Fig. 2 is a top view thereof;

Fig. 3 is a front elevation; and

Fig. 4 is a side elevation.

We claim:

The ornamental design for a bedframe support leg, substantially as shown.
